UNITED STATES PATENT OFFICE

156,922

COOKING STOVE CANOPY OR SIMILAR ARTICLE

Robert Sonntag, Dallas, Tex.

Application December 13, 1948, Serial No. 150,131

Term of patent 14 years

(Cl. D81—25)

To all whom it may concern:

Be it known that I, Robert Sonntag, a citizen of the United States, residing at Dallas, in the county of Dallas and State of Texas, have invented a new, original, and ornamental Design for a Cooking Stove Canopy or Similar Article, as shown, of which the following is a specification, reference being had to the accompanying drawing, forming part thereof.

I claim:

The ornamental design for a cooking stove canopy or similar article, as shown.

ROBERT SONNTAG.
